UNITED STATES PATENT OFFICE.

DONALD SINCLAIR, OF CHICAGO, ILLINOIS.

DUMP-CAR.

SPECIFICATION forming part of Letters Patent No. 651,428, dated June 12, 1900.

Application filed December 4, 1899. Serial No. 739,212. (No model.)

To all whom it may concern:

Be it known that I, DONALD SINCLAIR, a citizen of the United States of America, and a resident of Chicago, county of Cook, and

5 State of Illinois, have invented a certain new and Improved Dump-Car, of which the following, taken in connection with the accompanying drawings, is a specification.

My invention has for one object the provision of a dump-car which can be made to carry the load low and yet be dumped with facility and certainty.

Another object of my invention is the provision of an improved form of mechanism for 15 supporting the body of the dump-car, comprising a primary support or frame, a secondary support or strut, and means whereby in dumping the load is shifted from the point at which the primary support is carried in the 20 direction of a fulcrum-point against which the secondary support abuts when the body of the car reaches such a position as to require the elevation of the inner side thereof.

Another object of my invention is the provision of a dump-car which while strong and 25 simple can yet be constructed at a minimum cost.

The above, as well as such other objects as may hereinafter appear, I attain by means of 30 a construction which I have illustrated in preferred form in the accompanying drawings, in which—

Figure 1 is an end view of a car embodying my invention. Fig. 2 is a side view thereof. Fig. 3 is a section showing the operating parts with the car in level position, and Fig. 4 is a corresponding section showing the parts in the position which they assume when the load is being dumped.

35 Above a truck 5 is mounted a car-body 6, the weight of the latter being transmitted to the former by means of a frame or primary support 7, of approximately a triangular shape, the car-body resting upon the base of the triangle and the whole being carried at or near its apex upon a supporting part or pin 8, fastened to the truck.

Pivoted to the car-body, at one side of the middle part thereof, is a strut 9, provided at 40 one end with a slot 10, engaging a fulcrum pin or part 11, secured to the truck. At the apex of the primary support or frame 7 there

is a slotted opening 12, the purpose of which will be understood in connection with the description of the operation of the car, which I 55 will now proceed to describe.

The car-body when loaded stands in the position shown in Figs. 1, 2, and 3, the weight being carried upon the pin 8, which is at the upper end of the slot 12. The strut 9 is in the 60 position shown in Figs. 1 and 3, the fulcrum-pin 11 being at the lower end of the slot 10.

In order to permit the car-body to be carried in as low a position as possible, the pin 8 is made fast to the lowest convenient point 65 upon the truck, and the cross-beam 13 of the truck is beveled off on one end, as shown at 14, to permit the car-body to be dumped, although swung in such a low position.

In dumping the car the body is shifted side- 70 wise, the weight continuing to be supported upon the pin 8 until the upper end of the slot 10 strikes the fulcrum-pin 11, when the load of the car will be transmitted to the strut 9, carried by the said fulcrum-pin. After this 75 position is reached the highest side of the car-body is raised still farther to the position shown in Fig. 4, so as to cause the contents to be freely discharged. Such upward movement of one side of the car-body is permitted 80 by reason of the slot 12, the rotation of the body and load being about the fulcrum-pin 11 at this time.

From the above it will be seen that the load being carried when the car is in upright position upon the single point or apex of the frame it can be supported quite low upon the truck, and when desired to dump the load is shifted over to one side with very little force. After the strut has come to the position in 90 which it will transmit the load to the fulcrum-pin 11 the main body of the load has been shifted so far to one side that it requires comparatively very little force to lift the highest side of the car-body still farther into the 95 position shown in Fig. 4, so that the contents of the car will be, as stated, entirely and freely dumped.

While I have shown my improved car in the form in which I prefer to embody it, it is 100 obvious that in many of the details it could be changed without departing from the spirit of my invention. Where I have referred to a "supporting-pin" and a "fulcrum-pin," I de-

sire to be understood as applying the term in a sufficiently-broad sense to cover any equivalent device for performing the functions of the said pins, it being obvious, for example, 5 that instead of slotting the frame the bottom of the frame could be made with a bolt or eye engaging a slot in the supporting part. It is also obvious that it is immaterial whether the slot in the strut be made at one end or the 10 other.

The essential thing in my construction is that the load shall be, when the car is in level position, supported upon a point from which it can be shifted sidewise a considerable distance without encountering material resistance and that then the load should be transmitted to a point nearer the side of the car, the higher side of the car-body being then capable of still further elevation. 15

20 Having thus described my invention, what I claim as new, and desire to secure by Letters Patent, is—

1. A dump-car comprising a car-body, a truck-frame, a primary support, at the bottom of said truck-frame as described whereby the car-body is supported in a low position with reference to the truck, a secondary support, and means whereby the load of the 25 car is carried first on said primary support and then, when the car is partly dumped,

shifted to said secondary support to permit the elevation of the raised side of the car-body, substantially as described.

2. A dump-car comprising a car-body, a truck-frame, a primary support, a secondary support, a supporting-pin, a fulcrum-pin, and slots in both of said supports whereby in dumping the car the load is turned first about the supporting-pin as a center of rotation, and then shifted to the fulcrum-pin as a center of rotation, substantially as described. 35 40

3. A dump-car comprising a car-body, a truck-frame, a primary support, a secondary support, a supporting-pin, a fulcrum-pin, said primary support being formed approximately 45 of triangular shape carrying the car-body upon its base and being supported at or near its apex, a slot near the apex of said primary support and a slot in said secondary support whereby, in the dumping of the car, the 50 weight of the load is first moved about the said supporting-pin as a center of rotation, and then shifted to said fulcrum-pin, the raised side of the car being thereby further elevated, substantially as described.

DONALD SINCLAIR.
